UNITED STATES PATENT OFFICE.

WALTER COLLIS LOWTHER, OF EAST MOLESEY, ENGLAND.

APPARATUS FOR PLAYING GAMES.

1,216,333.

Specification of Letters Patent. Patented Feb. 20, 1917.

Application filed March 27, 1916. Serial No. 86,929.

To all whom it may concern:

Be it known that I, WALTER COLLIS LOWTHER, land agent, a subject of the King of Great Britain, residing at Hurst Side, River 5 Bank, East Molesey, Surrey, England, have invented a new or Improved Apparatus for Playing Games; and I do hereby declare the following to be a full, clear, and exact description of the invention, such as will 10 enable others skilled in the art to which it appertains to make and use the same.

This invention relates to apparatus for games of chance to be played by two or more players, and in which the player obtaining 15 the highest, or any given, number, is proclaimed the winner.

The apparatus, in accordance with this invention, consists essentially in a device in which a metal ball, marble, or the like, is 20 rolled down an incline into a globe or sphere where it meets with various obstructions, all tending to change the direction of its travel, and, emerging therefrom, passes through one 25 of several tubes or channels or grooves which conducts it into one of several numbered pockets or divisions formed in a tray attached to or formed upon the device where it finally rests. The player rolling the ball 30 is credited with the number in the pocket or divisions occupied by the ball and by arrangement between the players beforehand the one obtaining the highest number in a single round, or the highest aggregate in two or more rounds, is deemed the winner. 35 And in order that my invention may be fully understood I will now describe the same with the aid of the accompanying drawings which illustrate a convenient manner 40 of forming the device in accordance with the said invention.

Figures 1 and 2 are, respectively, a side elevation and a plan of the apparatus.

Fig. 3 is a sectional side elevation of the globe end of same, and

Fig. 4 is a section through line X—X, Fig. 1 showing particularly one of the ball or marble deflectors made use of.

Figs. 5 and 6 are respectively side elevation and plan of an additional deflecting device which may, if desired, be made use of.

Similar letters of reference indicate like parts throughout, where occurring.

a is a platform or bed of an oblong shape formed at one end with a number of pockets or divisions b each marked with a numeral (see particularly Fig. 2). At its other end,

in suitable brackets c provided thereon the sphere or globe d is mounted. This latter is preferably made in two halves hinged together as at e, Figs. 1 and 2. Thus the interior is rendered easily accessible while a chain such as f, Fig. 1, or other equivalent means may be made use of to prevent the upper half sphere being turned too far back on its hinge, and a locking device g may be used to securely hold the two parts in position when closed. h is the inclined chute leading from near the front end of the apparatus to the upper part of the globe or sphere d which latter may be formed with a smaller globular receiver d' at the top into which the chute h leads and which receiver communicates with the sphere or globe d aforesaid. h' is a tray formed at the free end of the chute h into which the balls or marbles are placed and from which they roll down the chute into and through the globe d.

A number (corresponding to the number of the pockets or divisions b) of inclined tubes or channels k lead from the lower part of the globe or sphere d to the several pockets or divisions b aforesaid (one to each). i i are branch pipes or tubes connecting the said tubes k to the globe or sphere d.

The ball or marble runs by gravitation down the chute h into the sphere or globe d, through which it passes into one of the inclined tubes k and emerges finally in one of the pockets or divisions b. And the object of my invention being to render it extremely uncertain as to which of the pockets or divisions the ball will settle in and thereby increase the element of chance in the game being played. I provide in the interior of the globe d a variety of obstructions to the ball in its traverse through the globe which serve to continually alter its course, and which obstructions are so arranged that it becomes a matter of impossibility to in any way direct or control the movement of the ball, once it is set rolling.

In Fig. 3 is illustrated a variety of the ball deflecting devices arranged within the globe d and which I employ, in accordance with this invention, for the above expressed purpose, that is to say:—

l is a swinging funnel which, though not so shown, may be corrugated, conveniently suspended by chains m to the interior of the upper part of the globe d and placed immediately below the ball inlet to the globe.

Within the funnel *l* and in the course of the falling ball I fit a cone shape deflector *n* which may conveniently be supported loosely upon a bracket arm *o* from the inner 5 wall of the funnel *l* in such manner as to be inclined or tilted by the impact of the ball or marble. This deflector may also be corrugated or ribbed or a three or four bladed propeller or fan may be suspended from the 10 top so as to catch the ball and revolve with it. From the deflector *n* the ball falls on to the side of the funnel *l* and its contact therewith causes the latter to swing or sway within the globe, (suspended therefrom as it is 15 by the flexible connections *m*), and the ball is caused thereby to take an uncertain course.

A dish or basket shaped device having a perforated bottom and as illustrated separately in Figs. 5 and 6 may be used as an 20 alternative to the above swinging funnel, or as an addition thereto if desired. The perforated bottom of the device may be conveniently formed of the crossed wires *p* attached at their ends to the wall *q* of the device to which latter are also connected the chains *r* by which it is suspended within the globe *d* in such manner as to be capable of swinging therein when the falling ball makes contact therewith, as it pursues its 25 course through the globe *d*.

In the lower half of the sphere or globe *d* I fit a bell dome *s* which not only still further deflects the ball in its traverse through the globe *d* but will be caused to ring by the 30 ball's impact therewith.

Below this bell dome *s* I fit a further deflector, seen particularly in Fig. 4, and upon which the ball falls after glancing off the bell dome. This, as will be seen, I make of 40 a star shape in plan view with sloping raised portions or ridges *t* on its upper surface. This deflector I arrange so that the concave portions of its edge partly surround the ball outlets *i* and tend to guide the ball into 45 same. It may yet, by chance, however fall upon or strike against one of the pins *u* arranged around and projecting from the inner surface of the lower part of the globe *d* and be still further deflected before reaching 50 its ultimate destination.

The device above described may be used in conjunction with any game that is played by numbers, thus forming an interesting means of obtaining numbers by chance as 55 are now usually secured by the throwing of dice, or the spinning of a tee-to-tum.

What I do claim as my invention and desire to secure by Letters Patent is:—

1. In a game apparatus the combination 60 of a base having a plurality of pockets, a hollow member supported by the base, a plu-

rality of inclined chutes communicating respectively at one end with the pockets and at their other end with the interior of the hollow member, and a single inclined chute 65 supported from the hollow member and communicating with the interior of the latter above the points of communication between the member and the chutes which deliver to the pockets. 70

2. In a game apparatus the combination of a base having a plurality of pockets, a hollow member supported by the base, a plurality of inclined chutes communicating respectively at one end with the pockets and 75 at their other ends with the interior of the hollow member, means for delivering objects into the hollow member above the points of communication between the member and the chutes, and means for changing the course 80 of objects passing through the hollow member under the influence of gravity.

3. In a game apparatus the combination of a base having a plurality of pockets, a hollow member supported by the base, a plurality of inclined chutes communicating respectively at one end with the pocket and at 85 their other ends with the interior of the hollow member, means for delivering objects into the hollow member above the points of 90 communication between the member and the chutes, and a deflector swingingly suspended within the hollow member for changing the course of objects passing through the hollow member under the influence of gravity. 95

4. In a game apparatus the combination of a base having a plurality of pockets, a hollow member supported by the base, a plurality of inclined sheets communicating respectively at one end with the pockets and 100 at their other ends with the interior of the hollow member means for delivering objects into the hollow member above the points of communication between the member and the chutes, a downwardly tapering tubular 105 member swingingly suspended within the hollow member, and a conical deflector supported within the tapering tubular member and positioned to be engaged by objects during their passage through the hollow member under the influence of gravity to deflect said objects against the tubular member to swing the latter and thus change the course 110 of said objects.

In testimony whereof I have signed this 115 specification in the presence of two subscribing witnesses.

WALTER COLLIS LOWTHER.
